(57) **CLAIM**

The ornamental design for a solar torch light, as shown and described.

DESCRIPTION

FIG. 1 is a perspective view of a solar torch light, showing my new design;

FIG. 2 is another perspective view thereof;

FIG. 3 is a front view thereof;

FIG. 4 is a rear view thereof;

FIG. 5 is a left side end view thereof;

FIG. 6 is a right side end view thereof;

FIG. 7 is a top view thereof;

FIG. 8 is a bottom view thereof;

FIG. 9 is another perspective view thereof, showing an in-use condition; and,

FIG. 10 is another perspective view thereof, showing another in-use condition.

The broken lines in the drawings represent unclaimed environmental subject matter and form no part of the claim.
